CONTAINER CLOSURE

William Vinson, Baltimore, Md., assignor to
 Crown Cork & Seal Company, Inc., Baltimore,
 Md., a corporation of New York

Application September 9, 1938, Serial No. 229,192

1 Claim. (Cl. 215—43)

The present invention relates to a container closure and refers particularly to a closure of the type provided with a non-metallic liner secured within the skirt of the closure against the top to prevent contact of the contents of the container with the closure.

Heretofore in closures of the "Mason" cap type comprising a metal shell and a vitreous liner, it has been customary to lock the liner within the skirt against the top by pressing the top portion of the skirt against the edge of the liner. While this arrangement is satisfactory to prevent contact of the contents of the container with the metal shell of the cap, it does not prevent the jar contents, dirt, or other foreign matter from entering between the liner and cap and becoming lodged behind the liner. This provides an unsanitary condition which has not heretofore been fully appreciated, primarily because the vitreous or opaque liner conceals any foreign matter which may penetrate between the top and liner.

The present invention is designed to eliminate this objectionable condition by positioning and clamping a gasket of rubber or other suitable material between the liner and the top of the cap to form a seal between the peripheral surfaces of the top of the cap and liner and thus prevent the entrance of foreign material behind the liner. Furthermore, the liner is preferably made of transparent glass to permit thorough inspection of the cap to determine if the seal is tight or if any foreign matter has penetrated behind the liner because of an imperfect seal.

With the foregoing and other objects in view, the invention will now be more particularly described, reference being had to the accompanying drawing in which:

Figure 1 is an interior plan view of the closure with a portion of the liner broken away;

Figure 2 is a section through the closure, and

Figure 3 is an enlarged fragmentary sectional view of the closure.

Referring now to the drawing, the numeral 10 designates a closure of the "Mason" cap type adapted to be applied to Mason jars or the like. As in this type of cap, the present closure comprises a substantially flat top 11 and a depending threaded skirt 12 formed integral with the top. The closure is preferably formed of metal and is provided with a liner 13 of glass or other suitable non-metallic material. This liner, similar to the "Mason" cap type, is formed with a centrally inwardly dished portion 14 and a flat

circular border 15. The top 11 is also provided with a central dished portion 16 and a flat peripheral border 17 corresponding to the border 15 of the liner.

In the usual "Mason" cap construction, the liner is constructed of an opaque vitreous material and is secured within the skirt so that the flat peripheral portions 15 and 17 of the liner and top are in contacting relation. While this construction prevents direct contact of the contents of the container or jar with the metal top, it does not form a tight seal between the liner and cap. Therefore, it is possible for the contents of the container and other foreign material to work past the portions 15 and 17 and enter the pocket 18 formed by the dished portions 14 and 16 of the liner and top. Furthermore, since the usual "Mason" liner is opaque, a cursory inspection of the cap will not reveal that any foreign matter has become lodged behind the liner.

With the present invention, this objectionable feature is overcome by providing a flat ring-like gasket of rubber or other suitable material 19 of a size to conform to the border portions 15 and 17 of the top and liner. This gasket is initially positioned in the cap, and the liner is then inserted so that the flat border portion 15 directly engages the gasket 19.

As will be observed, (see Figs. 2 and 3), the peripheral edge 20 of the liner is beveled, and after the liner and gasket have been inserted within the cap, the upper portion of the skirt 12 is bent or pressed inwardly against the bevel 20 to lock the liner and gasket in operative position within the closure. It is to be understood that in conforming the upper portion of the skirt to bevel 20, sufficient pressure is applied to the liner to place the gasket under compression to form a tight seal between the liner and cap sufficient to prevent the penetration of foreign matter within the pocket 18.

The liner 19 is preferably formed of clear transparent glass to permit inspection of the cap to determine whether the gasket forms a complete seal to prevent the entrance of foreign matter within the pocket 18. It is to be understood, however, that the invention is not limited to the use of a liner formed of transparent glass, since this additional feature is provided to facilitate inspection of the cap. As the gasket is designed to be placed under sufficient compression to form a tight seal, the liner may be formed of opaque vitreous or other suitable material.

It will be apparent that the present invention

provides an improved construction over the usual "Mason" cap and that it insures the use of a cap in which the liner not only functions to prevent contact of the contents of the container with the metal cap but also prevents penetration of the contents of the container or other foreign matter between the liner and cap, thereby eliminating an unsanitary condition which has heretofore prevailed in closures of this type.

10 It will be understood that the invention is not limited to the details of construction shown in the drawing and that the examples of the use of the device which have been given do not include all of the uses for which it is capable, and 15 that the phraseology employed in the specification is for the purpose of description and not of limitation.

I claim:

20 A closure having an overall top and a depending substantially cylindrical integral skirt, the skirt being provided with a circumferential portion extending from the top and below such por-

tion being threaded to engage the neck of a container, a vitreous circular liner disposed wholly within the closure and having an edge conforming to the said circumferential portion of the skirt at the top of the cap, said liner having a central 5 inwardly dished portion and a circular border presenting a flat top surface to the opposed top of the closure, the top of the closure having a central less pronounced dished portion and a circular border presenting a flat surface in an 10 opposed relation to the flat surface of the border of the liner and defining a circumferential shallow downwardly opening sealing groove in the top of the cap, and a gasket of resilient material disposed in the sealing groove and extending between the opposed flat surface border portions for sealing the closure against entrance of the contents of a container and foreign matter between the liner and the top whereby the same is prevented from collecting and presenting 15 an unsanitary closure.

WILLIAM VINSON.
